CLAIM

The ornamental design for a mobile phone stand, as shown and described.

DESCRIPTION

FIG. 1 is a perspective view of a mobile phone stand showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the mobile phone stand of FIG. 1, shown in a folded state; and,

FIG. 9 is an enlarged view of the portion of the mobile phone stand shown in the area designated as 9 in FIG. 2.

1 Claim, 9 Drawing Sheets
